MAGNETRON HAVING MAGNETIC BIAS OF SUCH STRENGTH AS TO MAKE CYCLOTRON FREQUENCY EQUAL TO TWICE PI FREQUENCY, USEFUL FOR COLD CATHODE OPERATION

Richard A. White, Horseheads, N.Y., assignor to Westinghouse Electric Corporation, Pittsburgh, Pa., a corporation of Pennsylvania

Filed May 3, 1963, Ser. No. 277,950
9 Claims. (Cl. 315—39.63)

The present invention relates generally to electron discharge devices and more particularly to devices of the magnetron type.

In the normal operation of devices such as magnetrons, electron emission is initiated and sustained through the thermal emission from an emissive surface cathode. A heating element disposed within the cathode is customarily utilized to bring the cathode to emission temperature.

In certain magnetrons, once the device has reached the operational state, it is possible to greatly reduce the heater current and hence the thermionically emitted electrons. In this instance, the bulk of the electrons necessary for sustaining operation are secondary emission electrons caused by electron back-bombardment of the cathode. Even with this secondary emission, the presence of some means for initially bringing the emissive surface of the cathode to operating temperature has always been required. The desirability of having a completely cold cathode, that is, one without a heater, is apparent from at least three standpoints. The first of these pertains to the overall efficiency of the device as it is obvious that in the supplying of current to the cathode heater, considerable power is consumed with a resultant lessening of the overall efficiency of the device. A second, although perhaps less obvious, reason for desiring a completely cold cathode device is from the standpoint of tube failure. One of the common causes of tube failure is the cathode heater. Much effort and money has been expended in the field of magnetrons, as well as in other types of discharge devices, to provide a cathode heater which will operate satisfactorily and which has suitable life. A third point to be considered is that of production cost. It is obvious that if the heating element of the cathode is eliminated without substantial increase in cost of production of the rest of the tube, that a more economically manufactured device will be obtained.

It is, therefore, an object of the present invention to provide an improved electron discharge device.

A further object is to provide an improved magnetron.

A still further object is to provide an improved electron discharge device of the cold cathode type.

Still another object is to provide an improved magnetron which is capable of cold cathode starting and operation.

An additional object is to provide an improved method of starting and operating a cold cathode magnetron.

Stated briefly, the present invention provides a cold cathode magnetron through synchronous secondary electron emission from the cathode. This emission is achieved by the proper selection of the magnetic field to provide that the number of epicycloidal scallops per anode segment is approximately one, or at least a small integral number, and that the cyclotron frequency is approximately an even multiple of the magnetron operating frequency.

Further objects and advantages of the invention will become apparent as the following description proceeds and features of novelty which characterize the invention will be pointed out in particularity in the claims annexed to and forming a part of this specification.

2

For a better understanding of the invention, reference may be had to the accompanying drawings, in which:

FIGURE 1 is a schematic illustration, partially in section, of a magnetron embodying the present invention taken along line I—I of FIG. 2;

FIG. 2 is a schematic illustration, partially in section, taken along line II—II of FIG. 1 to which certain components have been added;

FIG. 3 is a fragmentary view, partially in section, of a portion of the cathode and anode of the device and illustrating electron paths;

FIGS. 4a, 4b and 4c are illustrations of certain electron trajectories prevalent in magnetrons;

FIG. 5 is a graphical representation of the operational output of a device in accordance with the present invention;

FIGS. 6a and 6b are graphical representations of certain voltage characteristics useful in the explanation of the present invention.

With reference now to FIGS. 1 and 2, there is shown a magnetron which includes a centrally disposed cathode 10 which consists of a sleeve member 12, of a suitable material such as molybdenum having on the outer surface thereof an electron emissive coating 14. The emissive coating 14 is one which is a good secondary electron emitter, for example thorium oxide. Symmetrically disposed around and spaced from the cathode 10 so as to provide a region 16 therebetween is an anode indicated generally at 18. The anode 18 is comprised of an outer, substantially hollow cylindrical member 20 and an inner washer or apertured disc member 22. The two portions 20 and 22, made of a suitable material such as copper, may be formed from a single block of material by appropriate means such as by machining or may be separately formed and secured together by suitable means such as brazing. The inner portion 22 of the anode 20 is provided with a plurality of cavity resonators 24 of the well known hole and slot type. In the illustrated embodiment, eight such resonators equally spaced about the anode are shown.

As seen in FIG. 1, an output means 26, in communication with one of the cavities 24 by means of a slot 28 extending through the anode to the cavity, is provided to remove energy from the device.

The remaining basic components of the device are best seen with respect to FIG. 2 and include a pair of end plates 30 which may be vacuum sealed to the outer portion 20 of the anode 18 to maintain a vacuum within the interior of the device. Also provided are a pair of substantially U-shaped magnets 32 and a pair of substantially identical pole pieces 34, of satisfactory magnetic material such as soft iron, which extend from the magnets into the vacuum portion of the device, terminating in close proximity to the region 16 between the cathode and the anode. The magnets 32 and the pole pieces 34 collectively comprise the magnetic circuit of the device.

Also schematically illustrated in FIG. 2 is a potential means 36 which is connected, by means 38 and 40, respectively to the cathode 10 and the anode 18. While in the illustrated embodiment, the potential means 36 is shown to be a battery with its positive terminal connected to the cathode and its positive terminal connected to the anode, it is to be understood that, as is common practice in the art, the anode would in all probability be maintained at ground potential while the cathode would be connected to a suitable source of negative potential. Also, an electronic switch 37 might be used to rapidly turn on and off, that is, pulse the magnetron.

In normal magnetron operation, electrons are thermionically emitted from the cathode and, by virtue of

an electrical field extending substantially radially between the cathode and the anode and a magnetic field extending substantially perpendicular to the electric field and parallel to the axis of symmetry, follow what are generally described as cycloidal or, more correctly, epicycloidal paths. Inasmuch as each of the cavities is a resonant circuit, those electrons which are properly phased give up energy to the cavities to produce usable power which may be removed from the magnetron by some suitable means. One usual way to improve efficiency is to have many epicycloidal scallops per resonator. Inasmuch as the electrons, after having given up their energy to the cavities are collected on the anode, the plurality of scallops insures only a small amount of residual rotational energy associated with the electron when it strikes the anode. This action is one which is well known in the art and further discussion thereof is not deemed warranted here.

In the present invention, the efficiency of the magnetron is enhanced through the utilization of a completely cold cathode, which is made possible by the enhancement and synchronization of secondary electron emission. Through the proper selection of magnetic and electrical field parameters, preferably only one epicycloidal scallop per anode segment, and at most a very small integral number of scallops per anode segment is utilized. The single scallop per anode segment is illustrated by line 40 in FIG. 3.

The present invention provides such synchronous secondary electron emission by utilizing a magnetic field which is of a value such that the cyclotron frequency is twice (or an integral even multiple) of the operating frequency of the magnetron. The customary operating frequency of a magnetron is the pi-mode and magnetron types operating in this mode are well known in the art, for example, strapped magnetrons. The cyclotron frequency of a magnetron is known to be calculable by the following formula: $f_c = eB/2\pi m$, which is equal to approximately $28B$ (where f_c = the cyclotron frequency in gigacycles; B = the magnetic flux density in webers per square meter; e = electronic charge, a fundamental constant of nature with a value of 1.602×10^{-19} coulomb; m = electron rest mass, a fundamental constant of nature with the value 9.108×10^{-31} kilograms; and $2\pi = 6.283185$, a dimensionless geometrical constant).

FIGS. 4a, b and c will help clarify the present invention. As is well known, the trajectories of electrons within the magnetic field of a circular type magnetron, in the absence of a space charge, are epicycloids as illustrated in FIG. 4a. The diameter of the generating circle of the epicycloid is determined by both the electrical and magnetic fields. The rate of rotation of the generating circle is determined only by the magnetic field and is the cyclotron frequency as is set forth above, i.e., $f_c = 28B$. FIG. 4b, the curve of which may be designated a prolate epicycloid, illustrates the effect of initial electron velocity from the cathode.

The velocity (V_d) of the generating circle (the "drift" velocity) is given by the formula $V_d = E/B$ where E is the electric field between the anode and cathode in volts per meter and B is as defined above. Therefore, the radius of the generating circle is determined by mE/eB^2 . In the customary magnetron, the traveling electromagnetic wave on the anode structure 20 as is illustrated in FIG. 1 is synchronized with E/B (the "drift" velocity). Electrons which gain energy from the resonators 24 assume a trajectory as is shown in FIG. 4b. Those electrons which give energy to the resonators 24 assume a trajectory such as is illustrated in FIG. 4c (a curtate epicycloid) and gradually drift to the anode after having given up most of their energy. As has been stated, one method of improving efficiency has been to have a large number of such scallops per anode segment so that electrons following the curtate epicycloidal type of path have little energy left when they reach the anode.

The present invention provides that only a very small number, preferably one, of epicycloidal scallops per anode segment is utilized.

The operation of such a single scallop per anode segment device is as follows. Emission of an electron under a positive anode segment will cause the emitted electron to be accelerated and to arrive at the cathode under the next anode segment when that segment has become positive. Secondary electrons will be emitted and function in the same manner on the next half cycle of the magnetron oscillation. If an emitted electron loses energy to the field because it is emitted under a negative segment of the anode, it will continue to do so until collected by the anode. The relative phase of the oscillation of the magnetron is adjusted with respect to the emission time to insure that electrons in both categories are generated. Thus, it is seen that those electrons which are properly phased with the cavity voltages across gaps 25 serve to give energy to the magnetron while those which are improperly phased with respect to this are returned to the cathode in a manner to produce secondary electrons. Part of the secondary electrons will be properly phased and part will be improperly phased to give energy to the cavities. This mode of operation provides that a sufficient number of secondaries are produced and that the tube may be operated with no primary emission.

FIG. 5 is a curve resulting from data taken from a magnetron operated in accordance with the present invention. It is noted that the anode current peaks quite rapidly in a region in which the cyclotron to pi-mode frequency ratio is approximately two. Another peak (not illustrated) was found where this ratio was approximately four but it was noted this latter peak was of lesser height.

Thus, it is seen that by the proper selection of the cyclotron frequency that the secondary emission of the electrons is synchronized so as to provide an enhancement thereof.

The foregoing discussion has been premised upon the assumption that there are electrons available with which to start the aforescribed operation. The problem remains, however, as to the manner in which the first electron to initiate the aforescribed operation is produced. It has been found in practice that the action may be initiated by supplying a negative voltage pulse to the cathode of sufficient magnitude so that if an electron were emitted from the cathode it would reach the anode. Such a pulse source is shown schematically at 37 in FIG. 2. The above value of voltage is commonly referred to as the Hull cut-off value. This value is represented graphically in FIGS. 6a and 6b. After the above-described pulse has been applied, it was found that if the cathode voltage is then dropped to the normal operating level (the Hartree level) and if the above relationship of cyclotron frequency to operating frequency are observed, that complete cold cathode operation was initiated and sustained. By way of example, a device was operated with a Hartree level of 28 kilovolts; the application of voltage near the Hull cut-off value, approximately 61 kilovolts, for a period of .53 microsecond sufficed to initiate operation.

While it is not certain where the first electron necessary for operation of the device comes from, it has been theorized, although not proven, that the highly secondarily emissive material of the cathode (and this is particularly true in the case of thorium oxide) is slightly radioactive and as such emits high velocity beta electrons which have sufficient energy to escape from the coating. These electrons strike the anode with a velocity which is sufficient to effect X-radiation from the cathode which, in turn, initiates photoemission from the cathode and hence the electrons necessary for operation are available.

It is thus seen that there has been provided a device of the magnetron type capable of complete cold cathode

operation which is achievable through the synchronization of secondary electron emission from the cathode in the magnetron by making the magnetic field of such a value that the cyclotron frequency is twice the operating frequency or close thereto or any even multiple of the operating frequency or close thereto. A particular set of values for such a described device would be for a magnetron which is designed to operate in the pi-mode frequency at approximately 1.310 gigacycles. In such a device, the cyclotron frequency required would be approximately 2.620 gigacycles and from the above formula, where f_c is equal to approximately 28B, the magnetic field within the region 16 would be approximately 0.0935 weber per square meter.

While there have been shown and described what are at present considered to be the preferred embodiment of the invention, modifications thereto will readily occur to those skilled in the art. It is not desired, therefore, that the invention be limited to the specific arrangements shown and described and it is intended to cover in the appended claims all such modifications as fall within the true spirit and scope of the invention.

I claim as my invention:

1. An electron discharge device comprising a cathode capable of electron emission, an anode including a plurality of cavity resonators spaced from and circularly arranged about said cathode, said cavity resonators being primarily determinative of the operating frequency of said device, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic fields acting to impart a substantially epicycloidal motion to electrons emitted from said cathode, said magnetic field being of a value such that the frequency of said cycloidal motion of said electron is equal to approximately twice that of the operating frequency of said device.

2. An electron discharge device of the magnetron type comprising a cathode capable of electron emission, an anode including a plurality of cavity resonators spaced from and circularly arranged about said cathode, said cavity resonators being primarily determinative of the operating frequency of said device, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic fields acting to impart a substantially cycloidal type motion to electrons emitted from said cathode, said magnetic field being of a value such that the frequency of said cycloidal motion of said electron is equal to approximately an even integral multiple of the operating frequency of said device.

3. An electron discharge device of the magnetron type comprising a substantially circular cathode capable of electron emission from the outer surface thereof, an anode including a plurality of cavity resonators spaced from and circularly arranged about said cathode, said cavity resonators being primarily determinative of the operating frequency of said device, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic fields acting to impart a substantially epicycloidal motion to electrons emitted from said cathode, said magnetic field being of a value such that the frequency of said cycloidal motion of said electron is equal to ap-

proximately an even integral multiple of the operating frequency of said device.

4. An electron discharge device of the magnetron type comprising a cathode capable of electron emission, an anode including a plurality of cavity resonators spaced from and circularly arranged about said cathode, said cavity resonators being primarily determinative of the operating frequency of said device, and said device operative in the pi-mode, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic field acting to impart a substantially cycloidal type motion to the electrons emitted from said cathode, said magnetic field being of a value such that the frequency of said cycloidal motion of said electrons is approximately an even integral multiple of the operating frequency of said device.

5. An electron discharge device of the magnetron type comprising a cathode capable of electron emission including an electron emissive coating of thorium oxide thereon, an anode including a plurality of cavity resonators spaced from and circularly arranged about said cathode, said cavity resonators being primarily determinative of the operating frequency of said device, and said device operative in the pi-mode, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic field acting to impart a substantially cycloidal motion to the electrons emitted from said cathode, said magnetic field being of a value such that the frequency of said cycloidal motion of said electrons is approximately an even integral multiple of the operating frequency of said device.

6. An electron discharge device of the magnetron type comprising a cathode capable of electron emission including a thorium oxide coating thereon, an anode including a plurality of cavity resonators spaced from and circularly arranged about said cathode, said cavity resonators being primarily determinative of the operating frequency of said device, and said device operative in the pi-mode, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic field acting to impart a substantially cycloidal motion to the electrons emitted from said cathode, said magnetic field being of a value such that the frequency of said cycloidal motion of said electrons is approximately double the operating frequency of said device.

7. An electron discharge device of the magnetron type comprising a cathode capable of electron emission, an anode including a plurality of cavity resonators spaced from and circularly arranged about said cathode, said cavity resonators being primarily determinative of the operating frequency of said device, said device being operative in the pi-mode, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic field acting to impart a substantially cycloidal type motion to the electrons emitted from said cathode, said magnetic field being of a value such that the frequency of said cycloidal motion of said electrons is approximately twice that of the pi-mode frequency of said device.

8. An electron discharge device of the magnetron type comprising a cathode capable of electron emission including a coating of thorium oxide, an anode including a plurality of cavity resonators spaced from and circularly arranged about said cathode, said cavity resonators being primarily determinative of the operating frequency of said device, said device operative in the pi-mode, means for applying an electrical potential between said cathode and said anode whereby there is established an electrical field in the region therebetween, and means for the establishment of a magnetic field in the region between said cathode and said anode which is substantially perpendicular to said electrical field, said electrical and magnetic field acting to impart a substantially cycloidal motion to the electrons emitted from said cathode, said magnetic field being of a value such that the frequency of said cycloidal motion of said electrons is approximately twice that of the pi-mode frequency of said device.

9. In combination, an electron discharge device of the magnetron type comprising a cathode, including a layer of thorium oxide, capable of electron emission, an anode including a plurality of cavity resonators spaced from and circularly arranged about said cathode, said cavity resonators being primarily determinative of the operating frequency of said device, said device operative in the pi-mode, means for sequentially supplying first an electrical voltage pulse between said anode and said cathode of sufficient magnitude to draw an electron at the surface of said cathode to said anode and then for

5 applying an electrical potential between said cathode and said anode whereby there is established therebetween an electrical field of sufficient magnitude to sustain operation, means for the establishment of a magnetic field in the region between said cathode and said anode which is substantially perpendicular to said electrical field, said electrical and magnetic field acting to impart a substantially cycloidal motion to the electrons emitted from said cathode, said magnetic field being of a value such that the frequency of said cycloidal motion of said electrons is approximately twice that of the pi-mode frequency of said device.
